UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

SIDE FRAME.

Application filed September 28, 1923. Serial No. 665,427.

My invention relates to side frames for car trucks and has been primarily designed to provide a simple wrought metal construction which is both strong and stiff but comparatively light in weight.

The invention, generally stated, consists in forming a car truck side frame from a relatively thin sheet or blank of metal shaped with a plurality of symmetrically formed side frame portions and folded so as to provide the compression member, tension member and truck columns.

One of the principal features of the invention, particularly stated, is to provide a car truck side frame from a substantially square sheet-metal blank shaped to provide an inner wall and an outer wall disposed in spaced relation to each other, each of said walls having a bolster opening, a plurality of truck column portions, a plurality of top arch bar portions, and a plurality of bottom arch bar portions, the angular disposition of said bottom arch bar portions permitting of the formation of the side frame from a relatively small blank in which there is a minimum waste.

Another object is to provide a car truck side frame formed from a relatively small sheet-metal blank having a plurality of top arch bar portions, truck column portions, and bottom arch bar portions, said blank being folded along an axis of symmetry extending diagonally of the blank whereby the opposite edge portions thereof form the tension member with its bottom arch bar portions disposed at an angle to the top arch bar portions of the side frame, which angle corresponds to the angular relation of said opposite edge portions to the axis of symmetry of the blank.

A further object of the invention resides in the production of a wrought metal side frame having symmetrically formed side frame portions, the arrangement of said portions in the blank from which the side frame is formed being such that part of the metal forming the symmetrical side frame portions extends in the direction of its rolling while other portions of the metal forming the oppositely disposed symmetrical side frame portions is disposed in a transverse direc-

tion to its rolling as the result of folding the blank along an axis obliquely disposed with relation to the direction of rolling, said arrangement of the metal serving to greatly increase the strength value of the side frame and permit of its formation from relatively thin sheet-metal blanks.

A still further object of the invention resides in the provision of a wrought metal side frame formed from a sheet-metal blank shaped and cut to provide corresponding side frame portions, the opposite corners of the blank being cut away, and the corner portions adjacent the diagonally disposed axis of symmetry of the blank permitting of the upper ends of the bottom arch bar portions receiving the journal boxes at the ends of the side frame in a comparatively simple and reliable manner.

A still further feature of the invention consists in the method of manufacturing a car truck side frame by forming from a sheet of metal a substantially square blank and providing in said blank upon opposite sides of a diagonally disposed axis of symmetry corresponding side frame portions, some of said side frame portions being arranged adjacent opposite edges of the blank and at an angle to its axis of symmetry, folding the blank along a line which, throughout its length, is parallel to said diagonally disposed axis of symmetry, and uniting said side frame portions.

My improved method further consists in forming the blank with the bottom arch bar portions thereof disposed at substantially forty-five degrees with respect to the axis of symmetry extending from corner to corner of the blank, folding said blank along said axis, and uniting the bottom arch bar portions, said bottom arch bar portions being maintained in their same angular relation with respect to the axis of symmetry, but having the direction of rolling of the metal differently disposed in opposite adjacent bottom arch bar portions of the blank.

There are other features of the invention pertaining to the particular formation of blank and the details of construction of the side frame, all as will hereinafter appear.

In the accompanying drawings illustrat-

ing the invention, the scope whereof is pointed out in the claims:

Figure 1 is a view in side elevation of a car truck side frame constructed in accordance with the present invention.

Figure 2 is a vertical transverse sectional view on the line 2—2 of Figure 1.

Figure 3 is a detail cross-sectional view on the line 3—3 of Figure 1.

10 Figure 4 is a similar view on the line 4—4 of Figure 1.

Figure 5 is a detail cross-sectional view on the line 5—5 of Figure 1.

15 Figure 6 is a detail horizontal view on the line 6—6 of Figure 1.

Figure 7 is a detail view in side elevation of a modified construction of journal box connected to the end of the side frame.

20 Figure 8 is a detail cross-sectional view on the line 8—8 of Figure 7.

Figure 9 is a view of the relatively square plate from which the blank is cut, the dot and dash lines illustrating the outline of the plate and the full lines showing the contour 25 of the blank forming the side frame.

Referring to the drawings in which similar reference characters designate corresponding parts in the several views, my improved side frame is composed of an inner 30 sheet-metal wall 1 and an outer sheet-metal wall 2, each of said walls being provided with a plurality of side frame portions such as top arch bar portions 3, bottom arch bar portions 4, and truck column portions 5. The 35 lower edges of the top arch bar portions are provided with inwardly extending stiffening flanges 6, said flanges being continued around the junction of the top arch bar portions with the bottom arch bar portions to 40 provide stiffening flanges 7 arranged along the upper edges of the bottom arch bar portions. The truck column portions are formed along their outer edges with inwardly extending stiffening flanges 8, said flanges 45 forming continuations of the stiffening flanges 6 and 7 to which they are integrally connected for reinforcing adjacent portions of the side frame.

50 The lower edges of the top arch bar portions between the truck columns are provided with inwardly extending stiffening flanges 9, said flanges being continued across the top of the bolster opening and downwardly along the sides thereof, as indicated 55 at 10. The inwardly extending flanges 10 stiffen the truck column portions of the side frame and are preferably adapted to be overlapped and united by means of rivets 11 located between the offset portions of 60 the truck columns and their points of junction with the beam portion of the side frame extending beneath the bolster opening. The 65 stiffening flanges 10 bordering the truck columns are continued beneath the bolster opening, as indicated by the numeral 12.

The bottom arch bar portions 4 are provided along their lower edges with inwardly extending stiffening flanges 13, said flanges being continued upwardly at the same inclination of the bottom arch bar portions 70 and being designed to have connected thereto the journal boxes 14. The adjacent contacting face of the journal box is disposed at an angle corresponding to the angular disposition of the bottom arch bar portions, 75 rivets 15 being designed to pass through the inwardly extending stiffening flanges 13 and a suitable web portion 16 of the journal box.

The web portion 16 of the journal box forms a seating portion for the outer ends 80 of the bottom arch bar portions, portions of said web being shaped to embrace the inner and outer side walls of the side frame at their junction with the inwardly extending stiffening flanges 13, as indicated by the 85 numeral 17 in Figure 9. The web portion 16 of the journal box is connected thereto by a plurality of upwardly extending longitudinally disposed ribs 18, the outer ends of said ribs being preferably disposed in the same 90 plane as the ends of the side frame. The inner ends of the ribs 18 are connected by a transversely disposed wall 19, said wall uniting the inner edge of the web 16 with the inner side wall of the journal box. This arrangement of journal box and side frame end is of comparatively simple construction, it being observed that the vertical loads are transmitted through the reinforced web portions 16 as are also the longitudinal and 95 rotary forces developed under service conditions. The riveting of the box to the in-turned stiffening flanges permits of convenient assembling of the parts and, as will be observed, affords a very rigid connection 100 between the inner and outer side walls of the side frame to prevent their separation.

The inner edges of the flanges are also preferably welded at a plurality of spaced points, as indicated at 20, said welds being 110 advantageously located to prevent the separation of the inner and outer walls of the side frame at the critical points thereof.

Referring to Figure 9, my improved side frame is constructed from a relatively thin 115 sheet-metal plate cut square, as shown by the dotted lines in said figure. The corresponding side frame portions formed in the blank are disposed upon opposite sides of an axis of symmetry extended diagonally 120 of the blank and obliquely to the direction of rolling of the metal indicated by the arrow. The corners of the plate adjacent the ends of the diagonally disposed axis are cut away, as indicated at 21, said cut away portions constituting the respective ends of the side frame in which the bottom arch bar portions 4 thereof terminate. The cut away portions are preferably curved, as shown, and when the blank is folded the inner and 125 130

outer side walls thereof are angularly disposed at the ends of the side frame for cooperation with the vertically disposed reinforcing ribs 18 of the journal box of which they constitute continuations.

The opposite corner portions of the plate are cut away adjacent the beam member of the bottom arch bar portions, as will be observed by reference to Figure 9 in which the 10 contour of the side frame blank and the respective side frame portions are depicted in full lines.

The bottom arch bar portions of the side frame are formed along the opposite edge 15 portions of the square blank, the angular disposition of said bottom arch bar portions with respect to each other being that of a right angle and their angular relation to the diagonally extending axis of symmetry 20 being that of forty-five degrees. These same relative angular arrangements of the bottom arch bar portions are maintained in the completed side frame.

The blank is folded along a line parallel 25 to the diagonally extending axis of symmetry, it being observed that in the folding of said blank the direction of the rolling of the metal is disposed differently in adjacent arch bar portions, that is to say, the 30 direction of rolling of the metal is disposed longitudinally of one side frame portion and transversely of the other side frame portion in each side wall of the side frame. The relative strength of the bottom arch bar 35 portions is increased as the result of this construction in that some of the bottom arch bar portions take the stresses in the direction of rolling of the plate.

It will be observed from the foregoing 40 method of blanking a sheet-metal plate with corresponding side frame portions upon opposite sides of an axis of symmetry disposed obliquely to the direction of rolling of the plate, that a relatively small and thin metal 45 blank can be utilized and a side frame constructed which not only has the merit of being formed of light and reliable material, but the disposition of the metal in the several parts is such that the points of the side 50 frame subjected to greatest strains in service, are rendered exceedingly strong.

In Figures 7 and 8 a modified construction 55 of journal box is shown in which the outer upstanding ribs 18^a are continued upwardly and embrace the walls of the frame to which they are connected by means of rivets 18^b. The same general arrangement of web portion 16 and transverse wall 19 is maintained in this construction, the upstanding portions 60 of the outer ribs 18^a serving to provide a very rigid connection between the side frame and journal box in resisting transverse forces.

It will be noted that my improved construction of side frame end and journal box

involving the angular disposition of the contacting portions of the journal box with a similarly inclined end portion of the frame together with the disposition of the rivets of said connection, is such that the relative 70 rotative forces imparted to the journal box as the result of service conditions are effectively resisted.

I claim:

1. A car truck side frame formed from a substantially square sheet-metal blank folded to provide an inner wall and an outer wall arranged in spaced relation thereto, each of said walls having a plurality of truck column portions, a plurality of top arch bar portions, and a plurality of bottom arch bar portions, said bottom arch bar portions being disposed at an angle to the top arch bar portions corresponding to the angle of said bottom arch bar portions to the axis of 85 symmetry of the folded blank.

2. A car truck side frame formed from a substantially square sheet-metal blank folded to provide an inner wall and an outer wall arranged in spaced relation thereto, each of said walls having a plurality of truck column portions, a plurality of top arch bar portions, and a plurality of bottom arch bar portions, said bottom arch bar portions being produced from opposite edge portions 90 of the blank and disposed at an angle to the top arch bar portions corresponding to the angular disposition of the opposite edge portions 95 of the blank to the axis of symmetry of the folded blank.

3. A car truck side frame formed from a substantially square sheet-metal blank folded to provide an inner wall and an outer wall arranged in spaced relation thereto, each of said walls having a plurality of truck column portions, a plurality of top arch bar portions, and a plurality of bottom arch bar portions, said bottom arch bar portions being each formed from adjacent edge portions of the blank and disposed at an angle 100 of forty-five degrees with respect to the top arch bar portions of the side frame.

4. A car truck side frame formed from a substantially square sheet-metal blank folded to provide an inner wall and an outer wall arranged in spaced relation thereto, each of said walls having a plurality of truck column portions, a plurality of top arch bar portions, and a plurality of bottom arch bar portions, said bottom arch bar portions being formed from opposite edge portions of the blank and being united along their bottom edges.

5. A car truck side frame formed from a single square sheet-metal blank folded to provide inner and outer spaced side walls, each of said walls being formed with a plurality of symmetrically shaped side frame portions, some of said side frame portions comprising opposite edges of the blank.

- 6: A car truck side frame formed from a square sheet-metal blank folded to provide inner and outer spaced side walls, each of said walls being formed with a plurality of 65 truck column portions, a plurality of top arch bar portions, a plurality of bottom arch bar portions, said bottom arch bar portions comprising the oppositely disposed edge portions of the blank.
- 10 7. A car truck side frame formed from a square sheet-metal blank folded to provide inner and outer side walls, each of said side walls having a plurality of truck column portions, a plurality of top arch bar portions, and a plurality of bottom arch bar portions, said bottom arch bar portions comprising the oppositely disposed edge portions of the blank and being provided with 70 inwardly extending stiffening flanges.
- 15 8. A car truck side frame formed from a square sheet-metal blank folded to provide inner and outer side walls, each of said side walls having a plurality of truck column portions, a plurality of top arch bar portions, and a plurality of bottom arch bar portions, said bottom arch bar portions comprising the oppositely disposed edge portions of the blank and being provided with 75 inwardly extending stiffening flanges.
- 20 9. A blank for a side frame member of a car truck, said blank having a plurality of 80 symmetrically formed side frame portions disposed upon each side of an axis of symmetry diagonally dividing said blank.
- 25 10. A blank for a side frame member of a car truck, said blank being provided with 85 a plurality of symmetrically formed truck column portions, top arch bar portions and bottom arch bar portions disposed upon opposite sides of an axis of symmetry diagonally dividing the blank.
- 30 11. A blank for a side frame member of a car truck, said blank being substantially 90 square and having a plurality of symmetrically formed truck column portions, top arch bar portions, and bottom arch bar portions disposed upon opposite sides of an axis of symmetry diagonally dividing the blank, said bottom arch bar portions being formed of the oppositely disposed edge portions of said blank.
- 35 12. A blank for a side frame member of a car truck, said blank being square in shape and having a plurality of symmetrically 95 formed side frame portions disposed upon opposite sides of an axis of symmetry diagonally dividing the blank, some of said side frame portions being formed of the oppositely disposed edge portions of the blank.
- 40 13. A square metal blank for a side frame member of a car truck, said blank having an 100 axis of symmetry disposed diagonally of the blank and dividing the same into two portions each of which has a bolster opening, top arch bar portions, bottom arch bar portions, and truck column portions.
- 45 14. A square metal blank for a side frame member of a car truck, said blank having an axis of symmetry obliquely disposed with relation to the direction of rolling of the blank and dividing the same into two portions each of which is provided with a plurality of correspondingly formed side frame portions.
- 50 15. A blank for a side frame member of a car truck, said blank having an axis of symmetry obliquely disposed with relation to the direction of rolling of the blank and dividing the same into two portions each of which is provided with a plurality of top arch bar portions, a plurality of bottom arch bar portions, and a plurality of truck column portions.
- 55 16. A blank for a side frame member of a car truck, said blank having an axis of symmetry obliquely disposed with relation to the direction of rolling of the blank and dividing the same into two portions each of which is provided with symmetrically formed side frame portions.
- 60 17. The method of manufacturing a car truck side frame which consists in forming 105 a square sheet-metal blank with corresponding side frame portions symmetrically disposed with respect to an axis of symmetry passing between them, which axis is arranged diagonally of the blank, folding said blank along a line which, throughout its length, is parallel to said axis of symmetry, and uniting the side frame portions.
- 65 18. A method of manufacturing a car truck side frame which consists in forming 110 a square sheet-metal blank with corresponding top arch bar portions, bottom arch bar portions, and truck column portions symmetrically disposed with respect to an axis of symmetry passing between them, which axis is diagonally arranged with relation to the blank, bending corresponding portions of said blank to form flanges adjacent the aforesaid top arch bar portions, bottom arch bar portions, and truck column portions, folding said blank along a line which, throughout its length, is parallel to said axis of symmetry, and uniting said flanges.
- 70 19. A method of manufacturing a car truck side frame which consists in forming 115 a square sheet-metal blank with corresponding side frame portions symmetrically disposed with respect to an axis of symmetry passing between them, which axis is arranged obliquely to the direction of rolling of the metal of the blank, folding said blank along a line parallel to said axis of symmetry, and uniting said side frame portions.

20. The method of manufacturing a car truck side frame which consists in forming a square sheet-metal blank with corresponding side frame portions arranged upon opposite sides of a diagonally disposed axis of symmetry, which axis is obliquely disposed to the direction of rolling of the metal, bending corresponding portions of said blank to form flanges, folding said blank along a line which, throughout its length, ¹⁰ is parallel to said axis of symmetry, and uniting said flanges.

In testimony whereof I affix my signature.

DONALD S. BARROWS.
